UNITED STATES PATENT OFFICE.

LEON PIERCE, OF NEW YORK, N. Y.

COMPOSITE PENETRATOR AND SHELL FOR FILES.

Application filed October 25, 1927. Serial No. 228,566.

The main object of this invention is to provide a composite device for sinking a shaft and lining the shaft with a sleeve which is later to be filled with a concrete mixture to finally serve as a pile as used in building construction. The main difficulty in sinking shafts and sleeves simultaneously is that the sleeve adheres frictionally to the penetrator or whatever other device is used to sink the shaft, and as a consequence when the penetrator is extracted with the shaft which has been formed by it the shell is retained thereon and is also withdrawn. This makes it necessary to again perform the same operation until the shell remains within the shaft.

Another object of this invention is to provide a conical penetrator which is slipped into a hollow sleeve loosely and the space between the sleeve and penetrator is filled, at spaced-apart positions, with slip rods which are adapted to be extracted individually or collectively so that the penetrator, on remaining in the shell by itself, may be easily extracted therefrom without any frictional contact between the shell and penetrator.

Still another object of this invention is to provide a composite pile shaft penetrator which is hollow throughout its length, having at its lower end an anvil upon which a drop hammer, contained in the pile, contacts to sink the penetrator and form a shaft thereby.

The above and other objects will become apparent in the description below, in which characters of reference refer to like-named parts in the drawing.

Referring briefly to the drawing, Figure 1 is a perspective view of the composite pile shaft penetrator showing the shell mounted in place over the slip rods.

Figure 2 is a longitudinal sectional elevational view through the device, showing the drop hammer in partly raised position.

Figure 3 is a cross sectional view taken on line 3—3 of Figure 2 with several of the slip rods removed from place.

Figure 4 is a cross-sectional view taken on line 4—4 of Figure 2, showing the supporting ribs for the anvil.

Referring in detail to the drawing, the numeral 10 indicates the conical wall of the penetrator body. This conical wall is open at its larger end at the top and is also open at its

lower smaller end. The lower smaller end of the penetrator body is permanently closed by a rounded, preferably hemi-spherical, nose 11, which nose enters the soil first and is adapted to rest in being driven when coming to refusal soil. Intermediate the length of the penetrator and raised somewhat above the hemi-spherical nose 11 is a rigid internal flange 12 which forms an anvil seat upon which the hammer drops. This anvil seat is supported upon substantially heavy ribs 13 which extend radially toward the center of the penetrator and longitudinally downward throughout the remainder of the length of said penetrator. The anvil seat 12 has a collar 14 seated thereon. This collar forms part of a vertical guide post mounted axially within the penetrator. The lower portion 15 of the guide post extends downwardly from the lower face of the collar 14 and is threadably secured to the penetrator nose 11. The upper length 16 of the guide post projects from the upper face of the collar 14 at a position slightly above the upper end of the penetrator wall 10. Near the upper end of the upper section 16 of the guide post an external flange 17 is mounted rigidly upon said guide post and serves as a limiting member for limiting the upward stroke of a drop hammer 18 preferably conical in shape which passes upwardly and downwardly in a compartment 19 within the penetrator and is adapted to strike upon the collar 14 and exert a downward thrust upon the entire device thereby. This hammer has an axial bore 20 passing therethrough in which registers the upper section 16 of the guide post, which latter retains said hammer travelling in a vertical course. This drop hammer is connected by sling cables 21 and 22 to the usual and commonly used tackle, such as a pile driver or the like. The upper open end of the penetrator has a plurality of lugs 23 extending radially inward. These lugs are adapted to register in channels 24 of a removable anvil plate 25 when the latter is being fitted upon the penetrator. This removable anvil plate 25, after being given a short turn, will have its surface shoulder upon the lugs and will seat upon the limiting flange 17, and is designed to bear the brunt of the shock of the hammer striking the plate when the penetrator is being extracted from a shaft which it has formed. The removable anvil seat has an axial open-

ing therein through which the upper end of the guide post 16 passes and on either side of this guide post relatively large openings 26 are formed through which the sling cables 5 21 and 22 pass. A long conical shell 27 which may be made integral or of sections, is slipped over the penetrator preparatory to the latter being sunk into the soil. This shell has the same conformation as the exterior 10 of the penetrator but is of relatively large dimensions and the space existing between the shell and the wall of the penetrator is of sufficient dimension to permit the insertion of a plurality of slip rods 28 which 15 have eyelets 29 formed at their upper ends. These slip rods project a short distance above the upper open end of the penetrator so that the eyelets 29 may be readily attached to some removing tackle.

20 The device illustrated in the drawing is an arrangement of complementary elements which depend one upon the other for the useful functioning of the whole. A drop hammer 18 is contained movably within the 25 compartment 19 and is adapted to be used when the penetrator is either to pierce the soil or be extracted therefrom. The stroke of the drop hammer can be regulated by the tackle to strike either the collar 14 mounted 30 upon the anvil seat 12 or the removable anvil 25. When said drop hammer strikes the collar 14 the penetrator 10 and the shell 27 slipped over it and retained in place through the medium of the slip rods 28 35 pierces the soil and sinks until refusal soil is met with, thereby forming a relatively long conical shaft, which shaft is reenforced by the shell. When desiring to extract the penetrator from the shaft and shell the tackle is secured to one or more of the slip rods 28 which latter is then hoisted out of 40 place in the space between the shell and penetrator. It will be noted that these slip rods at their lower ends have a long taper 45 formed thereon so that these lower ends will not puncture the shell when being inserted in place between the penetrator and shell. After one or more of these slip rods have been removed, the penetrator fits loosely 50 in the shell and may be readily extracted by permitting the drop hammer to strike on its upward stroke the removable anvil plate 25 without danger of simultaneously extracting the shell. By securing the guide post at 55 two positions within the penetrator and making the collar 14 attached to the guide post, serve as an anvil plate upon which the hammer 18 strikes and securing the lower end of the guide post to the nose 11, the 60 shock that the drop hammer exerts upon the structure is distributed over a greater length and less danger of friction is thereby liable.

It is to be noted that certain changes in 65 form and construction may be made without

departing from the spirit and scope of the invention.

I claim:

1. In a device of the class described, a substantially conical penetrator, a drop hammer slidably mounted therein, a shell of the same conformity of the penetrator loosely fitted over the latter, means for frictionally securing the shell to the penetrator, said means being capable of withdrawal to assist in relieving the penetrator, and means for jarring said penetrator on the upward or downward stroke of the hammer. 70

2. In a device of the class described, a substantially conical penetrator, a drop hammer movable longitudinally therein, a shell having substantially the same shape of the penetrator loosely fitting over the latter, said shell and penetrator having a space therebetween, a plurality of slide rods arranged in spaced-apart relation in the space between the shell and penetrator, and means formed in the penetrator for jarring said penetrator on the upward or downward stroke of the hammer. 80 85

3. In a device of the class described, a hollow substantially conical penetrator, a drop hammer movable therein, a rounded nose at the apex end of said penetrator, a shell loosely fitted over said penetrator, said shell and penetrator having a space therebetween, a plurality of slide rods arranged in spaced-apart relation in the space between the shell and penetrator, one or more of said slide rods when slipped from place freeing 95 said penetrator from frictional contact with said shell, and means formed at the top and intermediate portions of said penetrator for jarring the latter on the upward or downward stroke of the hammer. 100 105

4. In a device of the class described, a hollow substantially conical penetrator, a drop hammer movable therein, a nose at the apex end of said penetrator, a shell loosely fitted over said penetrator, said shell and penetrator having a space therebetween, a plurality of slide rods arranged in spaced-apart relation in the space between the shell and penetrator, one or more of said slide rods when slipped from place freeing 110 said penetrator from frictional contact with said shell, and said slip rods having tapering lower ends, the upper ends of said slip rods having eyelets therein, and means formed at 115 the top and intermediate portions of said penetrator for jarring the latter on the upward or downward stroke of the hammer. 120

5. In a device of the class described, a penetrator, a shell having substantially the same shape as the penetrator and loosely fitting over the latter, said shell and penetrator having a space therebetween, means arranged in said space and frictionally engaging the shell and the penetrator to hold the same together, said means being removable 125 130

from said space to facilitate withdrawal of the penetrator from the shell.

6. In a device of the class described, a penetrator, means arranged therein for driving said penetrator, a shell having substantially the same shape as the penetrator and loosely fitting over the latter, whereby a space is formed between the shell and penetrator, means arranged in said space to cause said shell and penetrator to frictionally hold the parts together, said last named means being removable from said space to facilitate withdrawal of the penetrator from the shell.

7. In a device of the class described, a hollow substantially conical penetrator hav-

ing a rounded nose thereon, a guide post secured to said nose and extending longitudinally within said penetrator, a drop hammer slidably mounted on said guide post, means on said penetrator engageable by said hammer to jar the penetrator on the upward or downward stroke of the hammer, a shell having substantially the same shape as the penetrator and loosely fitting over the latter, whereby a space is formed between the penetrator and shell, and removable means extending into said space to frictionally hold the penetrator and shell together.

In testimony whereof I affix my signature.
LEON PIERCE.
